UNITED STATES PATENT OFFICE

CHARLES S. JOHNSON, OF CHAMPAIGN, ILLINOIS

VALVE

Application filed January 3, 1928. Serial No. 244,362.

The invention relates generally to valves and more particularly to valves for use on batch hoppers used for the measurement of aggregates and water for concrete mixtures.

5 The primary object of the invention resides in the provision of a novel valve construction whereby a discharge opening at the bottom of a batch hopper may be effectively closed by a valve member which provides a watertight seal and has a manually actuated operating means arranged to maintain the valve seated against the downward force exerted by the aggregate and water contained in the hopper.

10 Another object is to provide a flap valve structure wherein the force tending to open said valve serves to maintain the operating means in valve closing position.

15 A further object is to provide a batch hopper valve having a valve operating means which serves to apply a substantially uniform pressure to the valve member at all points about the valve orifice.

20 Other objects and advantages will become apparent from the following description and from the accompanying drawings in which:

25 Figure 1 shows a central vertical section through a batch hopper embodying the preferred form of the invention.

Fig. 2 is a fragmentary elevational view

30 of the hopper as viewed from the left in

Fig. 1.

Fig. 3 is a sectional view taken along the line 3—3 of Fig. 1, and

Fig. 4 is a fragmentary central sectional view showing the valve member in an open position.

35 While the invention is susceptible of various modifications and alternative constructions, I have shown and will herein describe

40 in detail the preferred embodiment, but it is to be understood that I do not thereby intend to limit the invention to the specific form disclosed, but intend to cover all modifications and alternative constructions falling within

45 the spirit and scope of the invention as expressed in the appended claims.

50 Referring more particularly to the drawings, a batch hopper 10 is shown supported beneath an aggregate bin having a discharge

shown). The hopper herein illustrated is of the type wherein the bulk aggregate 12 is released from the bin into the hopper 10 in sufficient quantity to fill the hopper 10 and pile into a conical mass within the hopper so that flow from the bin is stopped. The bin gate is then closed and the aggregate is totally submerged in water which is admitted from suitable points about the hopper. It

55 will be apparent that when water is admitted to the hopper, the cone of aggregate formed when filling the hopper will slump down below the final water level.

56 For the purpose of adjusting the hopper 10 so that it will contain the desired amount

60 of bulk aggregate, a section 13 is provided which may be adjusted vertically relatively to the main body of the hopper by any preferred means (not shown).

65 The hopper 10 illustrated herein is circular in form, having a vertical cylindrical wall 14 which has a downwardly converging portion 15 at the bottom thereof to form a circular discharge opening 16 for the emptying of aggregate and water from the hopper.

70 A vertically adjustable overflow spout 17 is provided near the top of the hopper whereby the total volume of aggregate and water may be controlled.

75 For the purpose of thoroughly submerging

the aggregate in the hopper, the device illustrated

80 provides for admitting water from below and serves to admit the water at a plurality of points about the bottom of the hopper so as to distribute it uniformly and insure the elimination of air pockets in the submerged aggregate.

85 In the form of the invention illustrated, this means is embodied in the valve structure

90 in such a manner as to distribute water from a supply pipe 20 having a control valve 21

95 and admit the water to the hopper through a port about the periphery of the discharge opening 16.

100 The valve structure provides an annular

wall 22 which is attached, as by welding, to

105 the inwardly converging wall 15 of the hopper, adjacent the edge which defines the dis-

charge opening 16. The wall 22 extends

105 downwardly a short distance and then con-

verges inwardly in spaced relation to the wall 15 to a point slightly below the discharge opening 16, thus forming an annular distributing passage 23 about the bottom of the 5 hopper 10. The lower end of the wall 22 provides an annular seat surrounding a valve opening 25 which is adapted to be closed by a gate or valve member 26 supported by an 10 arm or lever 27. Since the wall 22, which forms the seat for the valve member, extends 15 below the inner wall 15 which defines the discharge opening 16, it will be seen that when the gate is closed, a circular port 28 (Fig. 1) is provided through which water may pass from the annular distributing passage 23 into the hopper 10.

A radial extension 30 of the annular passage 23 is provided, into which the water supply pipe 20 is connected, thus furnishing a 20 common valve controlled source of water.

The valve member 26 comprises, in the present instance, an outer steel plate 31 of greater diameter than the valve opening 25, having mounted thereon a plurality of disks 25 32 of rubber or other resilient material which are held in position by a second rigid plate 33 adapted to fit within the valve orifice 25 when the valve is closed, thus providing for direct contact of the resilient members 32 30 and the valve seat.

It will be apparent that under the great weight of the aggregate and water contained in the hopper, a substantially perfect and uniform seating of the valve member 26 must be obtained. To this end the supporting arm 27 is attached to the valve member 26 centrally thereof by means of a bracket 35 which is attached to the plate 31 and pivotally connected to the arm 27 by a pivot 37.

40 Thus the force applied to the gate 26 by the arm 27 will be distributed about the valve seat to form an effective seal to prevent leakage of the water.

A second bracket or loop 38 on the plate 45 31 surrounds the arm 27 to retain the valve member 26 loosely in position thereon. The gate supporting arm 27 is in this instance provided with a transverse portion 40 (Fig. 1) which is pivoted in the plane of the valve seat and near the edge thereof on a pin 41 secured in a bracket 42 mounted on the valve structure.

Operating and locking means are provided 55 for the gate supporting arm 27. In its exemplary form this means comprises a toggle 43 arranged between a downwardly extending portion 44 of the arm 27 and an extension of the bracket 42, and includes a bell crank lever 45 pivoted at 46 on the bracket 60 42 and having one arm 47 thereof connected to the end of the downwardly extending portion 44 of the gate supporting arm 27 by means of an adjustable link 48. The other arm 51 of the bell crank 45 constitutes a hand lever, and by moving this arm 51, the toggle

43 is extended to move the arm 27 about its pivot point 41 to move the valve member 26 to closed position. By moving the toggle slightly past its extended position to what might be termed an over center position, the 70 valve may be locked against the valve seat and maintained in locked position by a lug 52 on the arm 47 of the bell crank which contacts the bracket 42 to prevent further movement of the toggle. It will be apparent that when the toggle is in such an over center position, the weight upon the gate 26 will tend to hold the gate operating means in locked position.

75 From the foregoing description it will be apparent that the invention provides a valve device for batch hoppers which may be quickly and easily moved from open to a locked closed position and that the valve device embodies complete and effective means for distributing the mixing water so as to make possible a more uniform measuring and proportioning thereof.

80 It will also be apparent that the invention provides a valve structure for batch hoppers wherein the valve member may support the weight of the aggregate and still prevent leakage of water from the hopper due to the equalizing action of the valve operating means which serves to effectively seat 85 the valve throughout its periphery and to lock the valve member in seated position.

90 I claim as my invention:

1. A valve for a batch hopper having a 100 discharge opening and comprising a body having a valve seat formed about said opening, a valve member, a supporting lever for said member pivoted adjacent the edge of said valve seat and having one end pivoted to said member centrally thereof, and operating means for said supporting lever comprising a toggle member having one end pivoted and stationarily supported relatively to 105 said body and the other end pivotally connected to said lever, said toggle being adapted when moved to extended position to move said valve member to closed position.

110 2. A valve device for a batch hopper having a discharge opening, said device comprising a body member having a valve seat, a valve member, a lever pivoted adjacent the valve seat and having one end connected to 115 said valve member, and means for swinging said lever to move said valve member to and from valve closing position, said means comprising a bracket stationarily supported relative to said body member, a bell crank lever pivoted on said bracket, one arm of said bell crank forming an operating handle and the other arm forming one link of a toggle, a link 120 completing said toggle having one end pivoted to the toggle arm of said bell crank and its other end pivotally connected to the lever supporting said valve member.

125 3. The combination with a hopper having 130

- 5 a bottom discharge opening, of a valve member adapted to close said opening and support the weight of the material in the hopper, a movable arm connected to said valve member centrally thereof and supporting the valve, and a toggle operatively associated with said arm and arranged to close said valve when moved to extended position.
- 10 4. A valve device for a batch hopper comprising a valve member, means providing a valve seat therefor, and operating means for said valve member comprising a toggle having an operative connection with said valve member centrally thereof to close said valve when moved to extended position, and arranged to maintain said valve in closed position when thrown into an over center position against the weight of the material in the hopper on the valve.
- 15 5. A valve device for a batch hopper comprising a valve member, means providing a valve seat for said member, operating means for said valve member comprising a toggle having an operative connection with said valve member to close said valve when moved to its extended position and arranged to permit movement to an over-center position, and a stationary member arranged to be engaged by said toggle member to limit such movement and to maintain said toggle member in said over-center position whereby to maintain said valve member in its closed position against the weight of the material in the hopper on the valve.
- 20 6. A valve device for a batch hopper comprising a valve member, means providing a valve seat for said member, operating means for said valve member comprising a toggle having an operative connection with said valve member to close said valve when moved to its extended position and arranged to permit movement to an over-center position, and means to limit such movement to maintain said toggle at substantially its extended
- 25 30 35 40 45

In testimony whereof, I have hereunto affixed my signature.

CHARLES S. JOHNSON.
